Primary Examiner — Holly Bayham*Assistant Examiner* — Rhea Shields(74) *Attorney, Agent, or Firm* — Cook Alex Ltd.(57) **CLAIM**

The ornamental design for a compact catheter package, as shown and described.

DESCRIPTION

FIG. 1 is a perspective view of a first embodiment of a compact catheter package, showing the new design;

FIG. 2 is a front elevational view thereof;

FIG. 3 is a top plan view thereof;

FIG. 4 is a bottom plan view thereof;

FIG. 5 is right side elevational view thereof. The left side elevational view being a mirror image thereof;

FIG. 6 is a back elevational view thereof;

FIG. 7 is a perspective view of a second embodiment of a compact catheter package, showing the new design;

FIG. 8 is a front elevational view thereof;

FIG. 9 is a top plan view thereof;

FIG. 10 is a bottom plan view thereof;

FIG. 11 is right side elevational view thereof. The left side elevational view being a mirror image thereof; and,

FIG. 12 is a back elevational view thereof.

In the drawings, the broken lines are for the purpose of illustrating environment only and form no part of the claimed design.

1 Claim, 2 Drawing Sheets(56)
